(57) **CLAIM**

The ornamental design for a rescue wedge as shown and described.

DESCRIPTION

FIG. 1 is an angled top perspective view of the rescue wedge.

FIG. 2 is a left side plan view thereof.

FIG. 3 is a right side plan view thereof.

FIG. 4 is a front plan view thereof.

FIG. 5 is a rear plan view thereof.

FIG. 6 is a top plan view thereof; and,

FIG. 7 is a bottom perspective view thereof.

Broken lines in the figures are not part of the claimed design.

1 Claim, 7 Drawing Sheets
